CHILD'S RECIPROCATING ROCKER

Filed May 28, 1928

FIG-1

FIG-2

12 A. C. ROHM, JR. INVENTOR

18 BY Merrill M. Blackburn
ATTORNEY

UNITED STATES PATENT OFFICE

ALBERT C. ROHM, JR., OF DAVENPORT, IOWA

CHILD'S RECIPROCATING ROCKER

Application filed May 28, 1928. Serial No. 281,030.

The present invention pertains to a child's reciprocating rocker which may be used both for dolls and children. Among the objects of this invention are to provide a novel 5 form of vehicle for the use of children; to provide a reciprocating seat of novel form which can be actuated by the feet of the person occupying the seat; to provide a toy of the character indicated of novel form and 10 operation; and such further objects, advantages and capabilities as will hereafter appear and as are inherent in the construction disclosed. My invention further resides in the combination, construction and arrangement 15 of parts illustrated in the accompanying drawing and, while I have shown therein what is now considered the preferred embodiment of this invention, I desire the same to be understood as illustrative only and not 20 to be construed in a limiting sense.

In the drawing annexed hereto and forming a part hereof, Fig. 1 is a plan view of my new form of rocker; Fig. 2 is a side elevation of the construction shown in Fig. 1; Fig. 3 25 is a front elevation of a modified form of the same; and Fig. 4 shows a detail of construction of a further modification.

Referring more in detail to the annexed drawing, the device comprises a pair of side 30 members 1 having a seat 2 between them, said seat having a back 3. Arranged rearwardly of the back 3 and secured to the upper edges of the side members 1 is a cross member 4 roughly representing a part of an aeroplane. 35 Forwardly of the seat and secured to the upper edges of the side members 1 is a tray 5 roughly representing a wing of an aeroplane. Secured to the upper face and forming a part 40 of this tray is a flange 6 which will serve to retain toys, food and the like for a child sitting on the seat 2. While it is preferable to have the tray horizontal as shown in Figs. 1 and 2, it may have the inclination of the upper edges of the side members as shown in 45 Fig. 3. A portion of the tray is cut out as indicated at 7 to leave a handle 8 which the child may take hold of while playing in this rocker. Preferably a strap or the like 9 is 50 provided so that the child will be more likely to be kept in the seat, if it has a tendency to

climb out. Steps 10 are provided on the sides of the toy so that a child may more readily climb into this vehicle. These also serve as stops and will be referred to again in this connection. 55

At the rear are wheels 11 which are mounted on any suitable pivots 12, in the present instance shown as bolts 1 having a plurality of washers 13 and nuts 14 thereon. It will be understood that any suitable mounting means 60 for these wheels may be provided, such as a bolt having a sleeve thereon against the outer end of which the washer 13 may be drawn by the nut 14 to provide a suitable space for the wheel 11 so that the same may roll freely. 65 At the forward end are pivots 15 upon which are mounted rocking elements 16 having rocking surfaces 17 concentric with the axes 15. Any suitable supporting brackets 18 are secured upon the inner surfaces of the 70 rocker elements 16 and serve as means to in part support the foot rest 19 extending across between the rocker elements 16. As the child rocks forwardly the rear edges of the rocker elements 16 strike at 20 against the forward edges of the steps 10. It will thus be seen that these serve as stops to prevent the device from rocking too far forwardly and catching a child's foot between the foot rest 19 and the lower edges of the side members 1. It will 75 also be seen that the forward edge of the foot rest 19 will strike the lower edges of the side members 1 as the child rocks backwardly. Spacing members 21 are preferably placed 80 between the body members 1 and the rocker elements 16 in order to prevent friction and wear between these elements. It is also preferred that suitable spacing means be provided to prevent the nuts on the pivot 15 from 85 binding the rocking elements 16 against the body members 1. 90

The tray 5 may be either permanently or detachably connected to the body members 1. In Fig. 4 is shown means for detachably fastening the tray to these members. This means consists of annular brackets 22 secured to the tray 5 and having perforations therein for the reception of pins 23 projecting from a body element 1. The other body element 1 has a latch 24 of any suitable type con- 95 100

nected thereto and a spring latch 25, similar in a general way to a screen door catch, is mounted upon the under side of the tray 5 to cooperate with the catch 24. It is preferred that a notch or slot be formed in the 5 face of element 24 adjacent the latch 25 so that the plunger 26 of the latch will fit therein and prevent the tray from swinging edge-wise with relation to the toy body. To detach the tray from the body it is only necessary to actuate the finger piece 27 which will withdraw the bolt 26 from the notch in the catch 24, thus making it possible to remove the tray for cleaning or any other purpose desired.

15 While this device is shown as being made largely of wood, it will be understood that it may also be made of sheet metal or other materials, if so desired.

20 A child sitting upon the seat 2 and having its feet resting on the foot rest 19 has only to flex and straighten its legs in order to operate this vehicle which can be easily caused to move back and forth.

25 It is of course understood that the specific structure disclosed herein may be departed from without departing from the spirit of my invention as set forth in the appended claims.

30 Having now described my invention, I claim:

1. A reciprocating rocker comprising side members, a seat connecting the side members, wheels always in contact with the floor or 35 other support upon which the device rests and supporting the rear ends of the side members, and rocker members pivotally connected to the forward portions of the side members.

2. A rocker of the character described, comprising side members having a seat between them, rolling supporting elements for the rear ends of the side members, eccentrically mounted rocker elements pivotally mounted adjacent the forward ends of the side elements, and a foot-rest connecting the rocker elements and located forwardly of the seat.

3. A toy of the character described, having a body supported at one end by wheels and at its other end by eccentrically pivoted rocker elements, said wheels and rocker elements being, when in use, always in contact with the support upon which the toy is resting, said toy having stops to limit the reciprocating movements of the body.

4. A reciprocating rocker having side elements connected by a seat and having reciprocating movement only, a tray connecting the forward portions of said side elements, rolling members sustaining the ends of the 60 side elements, stops on the side elements, and projections on part of said rolling members to engage the stops and serve as limiting means to limit the reciprocation of the rocker.

5. A toy simulating roughly an aeroplane 65 and comprising a body and forward and rear

planes mounted thereon, the forward plane having a handle thereon, a seat between the planes, rolling means to support the body, and cooperating means on the rolling means and body to limit the amount which the rolling means may roll.

6. A toy of the character described, having a body supported at all times at one end by wheels and at its other end by eccentrically pivoted rocker elements, said toy having stops to limit the reciprocating movement of the body, and means connecting the rocker elements whereby a child occupying the toy may cause same to reciprocate in a straight line.

7. A reciprocating rocker comprising side members, a seat connecting the side members, wheels supporting at all times the rear ends of the side members, rocker members pivotally connected to the forward portions of the side members, and a foot-rest connecting the 85 rocker members to make them function as a unit and to enable a child sitting in the rocker to cause reciprocation thereof in a rectilinear direction.

8. A toy of the character described, having a body supported at one end at all times by wheels and at its other end by eccentrically pivoted rocker elements, said toy having a rectilinear reciprocating motion and stops to limit the reciprocating movements of the body, a seat in the body, and a tray forwardly from the seat and provided with a handle to be grasped by a child sitting in the toy.

In witness whereof, I hereunto subscribe my name to this specification.
